UNITED STATES PATENT OFFICE

ARTHUR J. FILKINS, OF RIVERSIDE, ILLINOIS

VENTILATOR

Application filed September 18, 1929. Serial No. 393,375.

This invention relates to chimney tops or ventilators, but is more particularly adapted for use as a ventilator at a pipe terminal for conveying air, gases and the like from the interior of buildings, and the invention is to provide certain novel improvements in a ventilator structure of the type disclosed in U. S. Patent No. 1,728,494 granted to Harold Knutson for ventilator on September 17, 1929, and to improve ventilators having a mode of operation similar to the aforesaid type of ventilator in sundry details herein-after described and more particularly pointed out in the appended claims.

Among other objects, the invention is intended to provide automatic means in a ventilator of the type described in which a strong upward draft through the hood of the ventilator is attained, resulting in the creation of a vacuum at the top of the ventilator pipe and a strong upward draft through the ventilator pipe by which the velocity of the air currents through the hood of the ventilator and consequently the draft through the ventilator may be decelerated or retarded somewhat in accordance with the velocity of air currents from the outside playing upon the ventilator.

A still further object of the invention is to provide improved automatic means in the air passages of a hood surrounding the exhaust terminal of a ventilator pipe by which the upward draft in the air passages of the hood may be automatically retarded when the device is submitted to exceptionally high wind velocities, this automatic device being also adapted to function in normal use as a division plate in the air passages of the hood, having the double function of the automatic draft retarder and to a large extent the function of a division or partition plate in the draft passages capable of dividing the air currents and by reason of slight restrictions in the air passages tending to accelerate the air velocities over the top of the ventilator pipe.

Other objects of the invention will appear from the following specification, which is directed to the preferred embodiment of the invention as shown in the accompanying drawing forming a part of the specification, the

novel features being more particularly pointed out in the appended claims.

In the said drawing:

Fig. 1 is an elevational view, partly in section, of a chimney or ventilator top embodying my invention and having portions thereof broken away to illustrate the novel features thereof.

Fig. 2 is a detached perspective view of one of the pivotally mounted draft controlling devices adapted to be operated by the air pressure striking the ventilator hood.

The reference numeral 10 designates a section of pipe adapted to be secured to or forming a continuation of the upper end of a ventilator or chimney pipe and having formed in its upper edge portion a plurality of uniformly spaced notches 11, preferably of substantially V-shaped form. Secured to the outer surface of the pipe 10 and suitably spaced therearound and overlying and co-operating with each of the notched portions 11 are a plurality of upwardly tapered U-shaped draft members preferably in the form of a divided hood.

It is a convenient method of construction to form these draft members of one or more sheets of metal connected together in the form of a hood that will slip downwardly around the upper end of the pipe 10, the upwardly tapered draft passages being U-shaped as designated by reference character 12 and the outer walls thereof being indicated at 13. The material forming this hood having the divided upwardly tapered passages 12 is preferably brought between each of the draft members to a point where it contacts with the outer periphery of the pipe 10 as indicated at 14, at which points of contact with the pipe the hood may be secured to the pipe in any suitable manner, not shown, if a mode of securing other than frictional contact is desired. 15 is the usual ventilator cap, preferably being given a slightly conical shape, as illustrated in Fig. 1 and being supported by a plurality of spaced brackets 16, which brackets support intermediate the cap plate 15 and the hood 13 an annular supplemental cap plate 17 in the form of a frustum of a cone, the latter being riveted to the

100

brackets 16, which are given an angular outward bend as indicated at 18, to furnish a proper support for the supplemental cap plate, the brackets being thence deflected inwardly to a point adjacent the innermost peripheral portions of the hood, which may be attached thereto by suitable rivets, as indicated at 19, the brackets then extending downwardly and being supported by rivets or other suitable means 20 to the top of the pipe 10 between the notches 11. There will preferably be one of these supporting brackets between each of the upwardly tapered passages 13 of the hood. In this type of ventilator the upwardly restricted passages 12 are exposed to the action of lateral air currents by reason of the fact that the material 13 of the hood is cut away at an angle of forty-five degrees or more to the horizontal, as indicated at 21. Consequently, when lateral air currents strike the hood of the ventilator, traveling in the approximately horizontal direction, the further direction of travel of the air upon striking the hood 13 will be upwardly and due to the restricted passageway the pressure and consequently the velocity of the air will tend to increase.

The material of the upper end of the pipe adjacent the V-shaped notches 11 is preferably notched, as indicated at 22, and the edges of the material adjacent the notch 11, as indicated at 23, are bent outwardly in this type of ventilator, with the result that the currents passing over these flanged or bent edges in the upper end of the pipe are found to produce eddies or counter-currents with a tendency to vacuum at the upper end of the pipe 10, the air thus set in motion with any gases or impurities adjacent the lower end of the pipe 10 passing on upward through the upper end of the hood 13 and then outward from under the cap plate 17 or the top cap plate 15, a result that will be augmented by the usual air pressure from the outside of the ventilator when there is any wind blowing.

The type of ventilator as above described and claimed in the aforesaid prior patent is found to be highly efficient and in fact, under some conditions of lateral air pressure when exceptionally strong winds are blowing, the action of the ventilator may result in a too rapid current being produced through the device.

It is the chief object of the invention to remedy this situation and to otherwise improve the operation of the device, which I accomplish by the provision of the wind operated swinging vane (shown in Fig. 2), which is pivotally mounted and counterweighted so as to normally hang approximately vertically within the upwardly tapered passage 12 of each of the hood members 13. This swinging vane is designated generally by the reference character 25. It

is preferably a piece of sheet metal of substantially rectangular form and at its lower extremity and along the lower edge thereof it may be counter-weighted by rolling the sheet metal thereof, as indicated at 26, around a metallic pin 27 of a length equal to the width of the vane, or any other suitable counterbalancing or weighting means may be attached to the lower edge thereof. This vane 25 is preferably of a length sufficient to extend below the closed wall 13 of the passageways 12 in the hood for a considerable distance of the length of the vane, thus exposing the greater part of the vane below its pivotal mounting in the walls of the hood to the action of lateral air currents passing into and being thence deflected upwardly through the hood passages 12. These vanes 25 may conveniently be pivotally connected with the lateral walls of the hood passages 12 by means of pivot members of any desired construction.

One convenient means of constructing such pivotal attachment of the vanes is illustrated in Fig. 2, in which a cylindrical metallic shaft 28 is flattened as at 29 intermediate its ends and perforated in the flattened portion to take a rivet or pin 30 passing also through a perforation in the vanes 25. I prefer to bend the upper end of the vanes 25 along the approximate line at which the pivot shaft 28 is secured thereto, the bent or deflected portion above the pin being inclined at an angle to the body of the vane below the pivot pin, as indicated at 31. The material of the vane is also slotted by parallel cuts and the portions 32 between the slits deflected from the body of the material and sufficiently elongated or stretched so as to permit the insertion of shaft 28 under these deflected slotted portions after which the portions 32 are pressed upon and around the shaft, thus tending to more firmly anchor the pivot shaft 28 to the vanes. The degree of the aforesaid bend of the upper end 31 of the vane out of the plane of the lower body portion thereof will depend upon the size and construction of the hood 13 and upon the amount of maximum restriction that is desired in the passageway. The lateral walls of the hood passages 12 may be somewhat radially inclined, under which conditions the vanes 25 in order to be pivotally operative, will of course, of necessity have to be of a width equal only to the minimum distance between the side walls of the passage, and to prevent lateral play of the vanes, bushings 33 may be inserted on the ends of the shaft 28 to properly space the vanes 25 and prevent them from binding against any portions of the side walls of the hood passages.

The operation of the novel features of the improved hood will be understood from the aforesaid description, it sufficing further to say that when substantially longitudinal air

currents of exceptionally high velocity strike the projecting lower ends of the vanes 25, the vane 25 will tend to be rocked to the dotted line position as indicated in this view 5 adjacent the side wall of the main ventilator pipe 10, the upper end 29 striking the hood wall 13 with only slight impact or noise. This will result in partially or almost wholly, 10 restricting the air currents that may be allowed to pass upwardly through the ventilator, thus automatically in the case of exceptionally high wind velocities, regulating the vacuum that will be produced in the upper end of the pipe 10 and the consequent 15 discharge rate of the ventilator. The amount of the counter-weight applied to the lower end of the vane and other conditions attendant upon the construction of the hood passages and the vane may obviously be varied 20 during the course of manufacture to accommodate the device for use under various atmospheric conditions, and it will be seen that the invention provides means whereby too rapid interchange of air through the ventilators or chimneys may be automatically 25 prevented in cases of storm and exceptionally high wind velocities.

The present invention is not intended to be limited to the precise construction and arrangement shown and described, since various modifications may be made by those skilled in the art without departing from the purpose and spirit of the invention.

I claim:

1. In a ventilator or chimney the combination with a pipe of a hood surrounding the exhaust terminal of the pipe, there being a portion of the hood projecting above the upper end of the pipe, the said hood being formed 35 as an enlargement around the periphery of the pipe with spaced apart portions thereof formed inwardly to contact with the outer periphery of the pipe whereby to provide between said spaced apart inwardly formed 40 portions on the hood, a plurality of upwardly tapering draft passages outside of said pipe and communicating with the interior thereof at its upper extremity, a cap plate positioned 45 above said pipe and hood, and draft control 50 vanes, one of which is pivotally and swingably mounted within each of said draft passages in the hood, there being a portion at the 55 lower end of each of said pivotally and swingably mounted vanes projecting below the lower end of the draft passages in the hood, thus exposing the lower extremities of the said vanes to the action of air currents traveling in a general horizontal direction 60 toward the vertical axis of the pipe.
2. In a ventilator or chimney, the combination with a pipe having a plurality of V-shaped notches formed in its upper edge, of a plurality of draft members positioned around said pipe and co-operable therewith 65 in a manner to form a plurality of upwardly

tapered passages outside said pipe and adjacent said notches, a cap plate positioned above said pipe and members, and pivotally mounted partition plates within said draft members adapted to be operated to a position to substantially restrict the said upwardly tapered passages in the draft members upon the application of wind pressures or velocities above a predetermined degree to the said draft members.

3. In a ventilator or chimney, the combination with a pipe having a plurality of V-shaped notches formed in its upper edge, of a plurality of draft members positioned around said pipe and co-operable therewith in a manner to form a plurality of upwardly tapered passages outside said pipe and adjacent said notches, a cap plate positioned above said pipe and members, and pivotally mounted partition plates within said upwardly tapered draft passages being adapted to form normally a plurality of radially spaced passages within said members and also to be swung to positions to substantially restrict said draft passages upon the application thereto of abnormal air pressures or velocities.

4. In a ventilator or chimney, the combination with a pipe having a plurality of V-shaped notches formed in its upper edge, of a plurality of draft members positioned around said pipe and co-operable therewith in a manner to form a plurality of upwardly tapered passages outside said pipe and adjacent said notches, a cap plate positioned above said pipe and draft members, pivotally mounted partition plates within said upwardly tapered draft passages being adapted to form normally a plurality of radially spaced passages within said members and also to be swung to positions to substantially restrict said draft passages upon the application thereto of abnormal air pressures or velocities, and flanges projecting outwardly from the edges of said V shaped notches in the pipe and being adapted to lie adjacent the upper projecting ends of said pivotally mounted partition plates.

5. In a ventilator or chimney, the combination with a pipe, of a plurality of draft members positioned around said pipe and co-operable therewith in a manner to form a plurality of upwardly tapered passages outside said pipe, a cap plate positioned above said pipe and draft passages, and partition plates pivotally mounted in each of said draft members in a manner to form a plurality of radially exposed passages within said members, the lower ends of said partition plates projecting below the exposed lower ends of said draft members whereby to be accessible to air currents on the outside of said draft members and said pipe and operable by excessive air currents to a position to substan-

tially restrict said upwardly tapered draft passages.

6. In a ventilator or chimney, the combination with a pipe having a plurality of V-shaped notches formed in its upper edge, a plurality of U-shaped draft members uniformly spaced around said pipe adjacent said notches and co-operable with said pipe in a manner to form a plurality of upwardly 5 tapered passages outside said pipe and adjacent said notches, a cap plate positioned above said pipe and draft members, a plurality of pivotally mounted partition plates in said draft members adapted to form a plurality of radially spaced inner and outer passages within said members, the lower ends of said pivotally mounted partition plates extending below the lower ends of said draft members whereby said pivotally mounted plates may be acted upon by excessive air currents or pressures to substantially restrict the said 10 radially spaced inner and outer passages in the draft members, and outwardly inclined flanges along the upper edge of said V-shaped notches in said pipe whereby to permanently 15 restrict a sectional draft area of said draft passages.

7. In a ventilator or chimney, the combination with a pipe, a plurality of draft members positioned around said pipe in a manner to form a plurality of upwardly tapered 20 passages outside said pipe, a cap plate positioned above said pipe and members, means carried by the pipe for permanently restricting the cross sectional draft area through said draft members, and means adapted to divide the passages through said draft members into a plurality of radially spaced inner and outer 25 passages, said means being adapted to be operated by excessive lateral air currents to substantially restrict the cross sectional area 30 of said draft passages.

8. In a ventilator or chimney, the combination with a pipe having a plurality of V-shaped notches spaced around the upper end thereof, of a plurality of U-shaped upwardly 45 tapered draft members annularly spaced around said pipe and extending around the upper edge thereof, said members being adapted to co-operate with the outer face of said pipe in a manner to form a plurality of air passages adjacent said notches, pivotally mounted vanes in the respective U-shaped members being pivotally mounted in a 50 substantially vertical position with their lower ends exposed below the lower ends of the said U-shaped members to provide a plurality of radially spaced upwardly tapered 55 passages within said members, and a cap plate positioned above said members, said vanes and said pipe.

9. In a ventilator or chimney, the combination with a pipe, a plurality of U-shaped 60 upwardly tapered draft members annularly spaced around said pipe and extending

around the upper edge thereof and being adapted to co-operate with the outer face of said pipe in a manner to form a plurality of air passages around the upper end of said pipe, and a vane pivotally mounted in each 70 of the said air passages, the lower end of the vane being counter-weighted and projecting below the lower extremity of the said air draft passages whereby to be operated by lateral currents of air of predetermined velocity or 75 pressure to substantially restrict said draft passages.

10. In a ventilator or chimney, the combination with a pipe of a plurality of upwardly 80 tapered draft members annularly spaced around said pipe and extending above the upper edge thereof, and pivotally mounted partition plates in said draft members, the lower ends of said plates extending below the lower ends of said draft passages whereby 85 said pivotally mounted partition plates may be exposed to lateral air currents and rocked about their pivotal connections to restrict the cross sectional areas of said draft passages by lateral currents of air of predetermined 90 pressure or velocity.

In testimony whereof I have signed my name to this specification, on this 20th day of August A. D. 1929.
